UNITED STATES PATENT OFFICE.

JAMES W. McLAREN, OF MARIETTA, OHIO.

ROAD-MAKING MACHINERY.

1,369,977.

Specification of Letters Patent. Patented Mar. 1, 1921.

Application filed March 23, 1918. Serial No. 224,163.

To all whom it may concern:

Be it known that I, JAMES W. McLAREN, a citizen of the United States, residing at Marietta, in the county of Washington and State of Ohio, have invented certain new and useful Improvements in Road-Making Machinery, of which the following is a specification.

My invention relates to road making machinery and comprises a roller construction adapted to impart a hard smooth plane surface or a convex or a concave surface to a roadway and to provide berms and ditches and sloping lateral banks for the roadway. The supporting wheels are adapted to assist in the rolling which is done primarily by a plurality of vertically adjustable and axially reversible rollers and devices are provided for positioning the rollers vertically and maintaining them thus in operation.

I provide a roller or rollers in preference to a third or fourth axle, and space the rollers at equal or unequal distances between the axles and adjust them vertically in such manner as to prevent the formation of waves in the surface rolled; the tendency where an additional axle or axles is provided is to produce waves in the surface and when started the continuing action of the rolling machine usually intensifies them.

Further the driving power is distributed to act on all the wheels to minimize the disturbance of the material under the wheels due to the torque resulting from the wheel movement thereover. Also by using a plurality of rollers or idlers one may be so set or adjusted as to relieve the weight on the appropriate wheel in passing over a soft spot in the surface until the whole surface has been brought to the same plane and to a harmonious consistency. When the third or fourth axle is used the lineal weight per square inch of wheel contact is so reduced that it is unfit for compacting a road surface, while with my apparatus I first reduce the weight per square inch of wheel contact until the road surface is smooth and partly compact. By raising the idlers or rollers the unit weight of wheel contact is greatly increased.

The maximum compression of lineal weight per square inch of wheel contact is produced by lowering the rollers sufficiently to carry the weight of the end of the machine; this gives the machine a bearing of

three wheels as the rollers of today are constructed.

My devices may also be utilized in smoothing down old brick pavement roadways and to restore them to their original smooth surface as far as possible after the freezing and thawing of the winter season have worked their usual distorting effect. This operation can best be carried on as the frost is leaving the ground in the spring.

The Figures 1 to 10 inclusive are diagrammatic views of the machine showing a variety of arrangement and number of the rollers in the figures to and including Fig. 4^a; in Fig. 5 the rollers are depressed to operate transversely on a concave surface, in Fig. 6 the rollers are vertically retracted to operate transversely on a convex surface, in Fig. 7 the rollers are constructed and arranged to operate lineally on a concave surface, in Fig. 8 the rollers are axially reversed to operate lineally on a convex surface; in Fig. 9 the machine is shown moving around a curve; in Fig. 10 the trucks are shown in echelon or staggered formation whereby the machine is adapted to bring all the power of the rollers to bear on the sloping lateral bank of the roadway, and devices are hereinafter described for actuating the parts to assume the illustrated positions and for maintaining such positions while the rolling operation is proceeding. Fig. 11 is a top view of the machine without the sides; Fig. 12 is a longitudinal vertical section along the line A—B in Fig. 11; Fig. 13 is a top view of a modified construction wherein the front and rear fifth wheels are shown enlarged to embrace the driving wheels, and a side frame is shown lowered carrying a scraper blade thereon; Fig. 14 is an enlarged view of the steering and truck positioning device; Fig. 15 is an enlarged view of the transmission mechanism.

Referring to the drawings, 1 is the center frame or girders, 2 is the axle with the wheels 3, 4 thereon, 5 is an axle with the wheels 6, 7 thereon, 8 is the frame on which the roller 9 is suspended, 10 and 11 are roller manipulating screws, 12 and 13 are rollers provided in the varied construction of Figs. 2, 2^a, 14, 15, 16 are rollers in the varied construction shown in Figs. 3, 3^a, 17, 18, 19, 20, 21 are rollers in the varied construction shown in Figs. 4, 4^a, all of which are readily understood without further de-

scription. Figs. 1 to 10 inclusive are presented as diagrammatic showings, and Figs. 11 to 15 inclusive embody a physical structure based on the diagrammatic showing especially in Figs. 3 and 3^a, to which the ensuing description primarily refers; however other diagrammatic showings are contemplated in the description and claims wherever the language is pertinent. For instance, the showing in Figs. 9 and 10, or 7 and 8 are illustrative of the structure indicated in Figs. 3 and 3^a.

Throughout the specification wherever the term carriage is employed it comprehends the supporting wheels and their connecting axle and necessary associated structure for supporting an end of the apparatus. Consequently in Figs. 3 and 3^a one end carriage is shown at *e* including the wheels *f* and *g*, the axle *h*, and the fifth wheel and connected structure represented at *i*. A similar structure is of course seen at the other end of the vehicle but the parts are not marked.

Although operative structure and connections are not illustrated in the figures in question, yet it will be understood that they are diagrammatic representations shown for the sake of simplicity and to portray an idea merely, and the physical embodiment of this idea is illustrated in the figures on the following sheet of drawings. Referring now to Fig. 11 and following, 22 is the parallel girders composing the center frame of the machine, 23, 24 are heavy plates provided for receiving the heads 25, 30 of the king bolts, 26 is an axle, 27 is the driving gear thereon, 28 is a wheel and 29 is a stay rod supporting the casing inclosing the driving gear 27; 31 is the other axle carrying the driving gear 32, 33 is a wheel and 34 is a stay rod supporting the casing inclosing the gear 32. The engine 35 drives the gear 36 meshing with the gear 37 actuating differential 38 which in turn drives the gear 39, all mounted on shaft 40, which carries the worm 41 thereon to mesh with the driving gear 27 on axle 26, while the telescoping joint appears at 40^a and a universal joint provided in the shaft 40 appears at 40^b. The same construction identically indicated appears at the other end of the driving shaft, and the worm 42 thereon meshes with the driving gear 32 on the axle indicated at 31. At 43 is a gear mounted on shaft 40 controlled by the clutch 43^b actuated by the lever 43^a to set the gear 43 running with the shaft 40, whereupon gear 44 on shaft 47 is actuated, and when clutched through the manipulation of the lever 44^a and clutch 44^b drives shaft 47. On shaft 40 is also carried the gear 45 locked to the shaft by means of the clutch 45^a, whereupon said gear actuates gear 46 on shaft 47 locked thereto by the use of the clutch 46^a. By means of the clutches

43^b and 45^a—both clutches are operated by the same lever with connecting rods, and when one is in the other is out—the gears are turned in opposite directions which causes the roller to run forward or backward with equal ease. Shaft 47 at one end carries the gear 48 and at the other end the gear 49, adapted to mesh respectively with the racks formed on the turn-tables 50, 51. Gear 49 is locked to the shaft 47 by the clutch 52 actuated by the lever 53 through the rod 53^a controlled by the lever at 53^b; lever 53 is pivoted at 54 and is connected pivotally at 56 with the block 57 having the tooth 58 adapted to enter the opening 59 in the turn-table 51, to lock the said turn-table in any position to which it may have been rotated through the gear 49 and associated mechanism described above. By this means the truck is first directed as desired and then fixed in the desired position to effect the staggering shown in Fig. 10; the other truck is similarly manipulated and controlled through the mechanism appearing at 60, 61, but when not locked the gears 48, 49 are revolved in the same direction, causing the wheels to track; or one truck can be set at any angle and the gears 48, 49 being kept running in the same direction the staggered position will be created. Or one of the carriages may be positioned at such angle with the center girder structure as desired and the steering may be done by manipulating the devices controlling the other carriage; manifestly the vehicle may be steered from either end thereof as desired. The wheels, as 28, may be made axially reversible to produce desired rolling effects, it being apparent that ordinarily the edge portions of the surface being rolled will be under the rolling influence of the four wheels rather than of the intermediate rollers.

Rollers are shown at 62, 63, 64, journaled in the frames 65, 66, pivotally supported at 65^a. These frames are each toothed or provided with a rack as appears at 65^b, and are adapted to be actuated up and down through the worms or screws respectively shown at 65^c and 66^a. Worm 66^a is operatively connected with the bevel gear 67 adapted to mesh with the gear 67^a carried on the lateral shaft 67^b driven by the bevel 68 thereon meshed with the gear 68^a on the shaft 47, driven through the transmission mechanism above described. A similar mechanism for manipulating the frame 65 to position the rollers 63, 64 through the rack 65^b is provided but not here shown in detail.

Referring now to Fig. 13, therein are shown modified constructions including the large turn-tables 130, 131 having the internal racks respectively 132, 133 actuated through the worm and gear constructions shown at 134, 135, and 136, 137. At 138 is a ring adapted to carry the scraper or

grader 72^b, the rollers 62, 63, 64 having first been removed. These modified forms may be introduced when more power or compactness is desired in the construction for 5 particular kinds of work.

What I claim is:—

1. Automobile road making machinery comprising carriages connected by a center girder, devices carried thereon for positioning said carriages in staggered relation to each other, and means carried thereon for locking the same in said position during the operation of the vehicle, and rollers carried by said center girder adapted to contact with the surface to be operated upon. 10
2. Automobile road making machinery comprising carriages connected by a center girder, devices carried thereon for positioning said carriages in staggered relation to each other, and means carried thereon for locking the same in said position, and rollers carried by said center girder and means for rendering said rollers vertically adjustable 20 to increase or diminish the pressure thereby exercised upon the surface of the roadway. 25
3. Automobile road-making machinery comprising carriages connected by a center girder, frames disposed on said girder, rollers mounted in said frames, and means 30 adapted to adjust said frames vertically.
4. Automobile road-making machinery comprising carriages connected by a center girder, frames disposed on said girder, rollers mounted on said frames, a rack 35 formed on each of said frames, a worm adapted to engage each of said racks, and means for operating said worm to accomplish the vertical adjustment of each of said frames.
- 40 5. An automobile road-rolling apparatus comprising carriages having wheels constructed also for rolling purposes, a center girder connecting said carriages, provision for suspending one or more rollers from 45 said center girder intermediate said carriages, and means for vertically adjusting the position of said roller or rollers.
- 50 6. An automobile road-rolling apparatus comprising carriages having wheels constructed also for rolling purposes, a center girder connecting said carriages, axially reversible rollers depending from said center girder intermediate said carriages, and means for vertically adjusting the position of said 55 roller or rollers.
7. An automobile road making vehicle comprising swiveled end carriages therefor connected by a center girder, turn tables

carried upon said center girder, means for manipulating said turn tables to position 60 said carriages, and means for locking said turn tables to maintain said carriages in the desired positions.

8. An automobile road making vehicle comprising swiveled end carriages therefor 65 connected by a center girder, turn tables carried upon said center girder, means for manipulating said turn tables to position said carriages, and means for locking said turn tables to maintain said carriages in the 70 desired positions and simultaneously neutralizing said manipulating means.

9. An automobile road making vehicle comprising swiveled end carriages connected by a center girder, turn tables mounted 75 thereon, frames supported on said center girder, rollers carried in said frames, and separate means actuated by the vehicle motive power to transmit motion to the said wheels, to actuate said turn tables, and to 80 position said frames.

10. An automobile road making vehicle comprising supporting end carriages connected by a center girder, pivoted frames carried by said girder, a road roller supported by each of said frames, means for actuating said frames independently of each other whereby said rollers are severally positioned to bear upon the roadway with the degree of pressure desired. 90

11. An automobile road rolling apparatus comprising two carriages preferably each having two wheels thereon adapted both for carrying and rolling purposes, said wheels being axially reversible to produce desired 95 rolling effects, a center girder structure uniting said carriages, a plurality of rollers suspended from said center girder intermediate said carriages, and means for vertically adjusting said rollers either singly or in 100 groups.

12. Automobile road making machinery comprising two carriages connected by a center girder structure, devices carried thereon for positioning a carriage at an 105 angle desired with said girder structure, means for locking said carriage in said position, steering means provided to manipulate said other carriage as desired to give to said vehicle the proper direction of travel. 110

In testimony whereof I affix my signature in the presence of two witnesses.
